UNITED STATES PATENT OFFICE.

FREDERICK C. BILLINGS, OF MILWAUKEE, WISCONSIN.

MUSIC-ROLL-SUPPORTING CLAMP.

Application filed January 24, 1919. Serial No. 272,820.

To all whom it may concern:

Be it known that I, FREDERICK C. BILLINGS, a citizen of the United States, residing at Milwaukee, county of Milwaukee, and State of Wisconsin, have invented new and useful Improvements in Music-Roll-Supporting Clamps, of which the following is a specification.

My invention relates to improvements in music roll supporting clamps.

The objects of my invention are to provide a form of clamp adapted to prevent a music roll from unwinding from its spool; to prevent the spool from rotating upon, or 15 rolling along, a table, shelf, or other support, or to hold the spool, if desired, entirely out of contact with the support; to support the spool from the roll in a partially unwound condition, for display purposes; and to provide means to facilitate the adjustment of a music roll in the spool box, and its removal therefrom, by frictionally retarding the initial unwinding operation, and by preventing the roll from 25 unwinding after it has been rewound upon the spool, preparatory to its removal from the spool box.

In the drawings:—

Figure 1 is a front elevation of my improved roll supporting clamp, as it appears in use, the music roll being illustrated as it appears when held by the support wholly out of contact with the surface of a piano top, or other supporting surface.

Figure 2 is a side elevation of the same, showing the music roll in cross section.

Figure 3 is a view illustrating the use of my improved clamp to facilitate adjusting a music roll in the spool box, a portion of the player piano being illustrated in elevation, with the spool box open.

Figures 4, 5, and 6 are views showing modified forms of construction, in side elevation.

Figure 7 is a perspective view of a fourth modification.

Like parts are identified by the same reference characters throughout the several views.

In Figures 1 and 2, A—A are spool heads, 50 and B is a music roll of the ordinary type used for a player piano. A resilient clamp, having an arcuate portion C, downwardly projecting legs D, and arcuate arms E, is adapted to embrace the roll, and is formed 55 of a flat strip of resilient sheet metal, bent in such a manner as to form the members

C, D, and E, above mentioned. The legs D are preferably outwardly inclined, and are formed by bending intermediate portions of the strip outwardly in the form of 60 divergent loops, preferably V-shaped in form, as shown in Figure 2. These loops and the connecting arcuate portion C are preferably encased in a rubber sheath or jacket F, comprising a piece of a rubber tube, slipped or forced into position from one end of the strip.

I preferably extend this jacket upwardly along the legs to a point adjacent to the junction of the legs with the arms E, and 70 preferably utilize the tube to cover the portion C, whereby this non-metallic covering is brought into frictional contact with the outer surface of the roll. Where the jacket is composed of rubber, the clamping pressure will develop a considerable degree of 75 friction upon the roll, and in any case, the friction of the jacket, or of the clamp itself, will ordinarily be sufficient to prevent the roll from accidentally rotating within 80 the clamp. The arcuate portions are preferably of sufficient length to extend about three-quarters of the way around the roll, and the normal curvature is such that the arms E require to be separated from normal 85 position when the device is applied to the roll, whereby the resiliency of the material will be made effective to exert the desired clamping pressure. At the ends of the arms E, I preferably bend the material of which 90 it is composed, into the form of outwardly projecting eye pieces G, which are adapted to serve as handles to facilitate removing the device from the roll. The diverging portions of the legs formed by doubling or 95 bending the metal strip upon itself, facilitate expanding the clamp to receive the roll, without approaching the elastic limit of the material.

In Figure 3, it will be observed that it is 100 possible to adjust the roll in the spool box of a player piano, and to partially unwind it preparatory to connecting it with the active roll of the piano. This unwinding operation is possible, for the reason that the 105 roll is unperforated near the end thereof, and my clamping devices do not have sufficient tension or clamping pressure to prevent the strip from being pulled, and the roll unwound from within the clamping device, particularly where only a sufficient length of the unperforated portion of the

strip is unwound to allow it to be carried over the tracker bar, and connected with the active roll indicated at J in Figure 3. By thus leaving the clamp in position until 5 the music roll has been adjusted, and connected with the active roll or spool of the player piano, I prevent the paper from unwinding or springing away from the spool by its own resiliency, before it has been 10 properly adjusted and connected with the active roll. After the strip of paper has been unwound sufficiently to permit such connection, and either before or after the connection is actually made, the clamp may 15 be removed, and the music roll released for operation. The spool will be held under tension by the spindles on which it is mounted, and the paper cannot unwind accidentally, because the end of the strip will be 20 held under tension, either by the operator, or by the active roll, if it has been connected therewith.

In Figures 3 and 4, it will be observed 25 that the support is formed of round wire, the end portions of which constitute legs d, having their extremities bent at right angles to the legs to form foot pieces k. The intermediate portions form arcuate arms l, with an upwardly projecting central loop 30 m. This clamp is not adapted to hold the spool heads out of contact with the support.

In Figure 5 the construction is similar to that disclosed in Figures 1 and 2, but the device is inverted, and the end portions of 35 the material extended to form legs H and eyes G' at the extremities, which constitute foot pieces,—the folded portions D', which correspond structurally with the legs D of Figures 1 and 2, constituting upwardly projecting ears, which are adapted to serve as 40 handles to spread the clamp when applying it to, or removing it from, the roll. In this view, the arcuate portion C' bears upon the top of the roll, and the arms E' extend 45 downwardly. This structure may of course be formed of wire or of a flat strip or band of resilient material, as may be preferred.

In Figure 6 the structure is very similar to that in Figures 1 and 2, except that the 50 legs D'' are of eye form, and the arms E'' are carried upwardly far enough above the roll, and are out-turned in open curves, to serve as handles G''.

In Figure 7, a single piece of resilient 55 wire is illustrated as having been looped and crossed to form a closed eye m', arms l', legs d', and rectangularly bent foot pieces k', all similar in function and relative position to the structure shown in Figure 4, but 60 differing in form.

In Figures 4 to 7, inclusive, no rubber covering is shown, it being deemed unnecessary to repeat the illustration of this simple feature in all the modifications illustrated.

65 A rubber covering is merely desirable to

prevent marring highly finished surfaces, and as applied to the arcuate portions it increases the friction upon the roll. But it is not essential to the operation of the clamp.

In the constructions shown in Figures 3 to 7, inclusive, the legs or foot pieces project outwardly to a somewhat greater distance from the axis of the spool than the radii of the spool heads, and they are therefore adapted to prevent the spool from rolling along the surface of a table or other support, even in cases where they are not made of sufficient length to hold the spool with the heads above such surface. It will also be understood that if desired, a plurality of these clamps may be employed, in which case they may be adjusted at opposite sides of the longitudinal center of the roll, thereby making it unnecessary to depend upon the width of the clamp to prevent the roll from tilting in case the legs and foot pieces project far enough to hold the roll with the spool heads above the supporting table. Where a single clamp is used, it can easily be adjusted at the center 90 of the roll, owing to the fact that all ordinary music rolls are provided with a tapered extremity, which is exposed to view, and provided with a connecting ring or link. The clamp will be adjusted so as to engage 95 this tapered extremity of the roll in proximity to the connecting ring or link, and when so adjusted, it will occupy a central position between the spool heads.

I claim:—

1. The combination with a music roll and its winding spool of a resilient clamp having a pair of arcuate clamping arms adapted resiliently to embrace a roll between the spool heads, members on said clamp integral 105 with said arms and projecting outwardly in diverging directions substantially radially of the roll beyond the spool heads, said members being adapted to engage a supporting surface to prevent the roll from traveling along the surface and the clamp being releasable by one hand of the operator engaging said projecting members, the other hand being thereby left free to hold the roll.

2. The combination with a music roll and its winding spool, of a resilient clamp having a pair of arcuate clamping arms adapted resiliently to embrace a roll between the spool heads, loops on said clamp integral 115 with said arms and projecting outwardly in diverging directions substantially radially of the roll beyond the spool heads, said loops being adapted to engage a supporting surface to prevent the roll from traveling along the surface, a resilient connection between 120 said loops, curved to conform to and engaging the periphery of the roll, whereby the members may be urged together to separate said arms and release the roll, and the clamp being releasable by one hand of the operator 125 130

engaging said loops, the other hand being thereby left free to hold the roll.

3. The combination with a music roll and its winding spool, of a resilient clamp having a pair of arcuate clamping arms adapted resiliently to embrace a roll between the spool heads, members on said clamp connected to said arms and projecting outwardly in diverging directions substantially 10 radially of the roll beyond the spool heads, said members being adapted to engage a supporting surface to prevent the roll from traveling along the surface, a resilient connection between said members curved to conform 15 to the curvature of the roll and adapted to engage the roll with said arms, whereby the members may be urged together to separate said arms and release the roll, and the clamp being releasable by one hand of 20 the operator engaging said projecting members, the other hand being thereby left free to hold the roll.

4. The combination with a music roll and its winding spool, of a resilient clamp having a pair of arcuate clamping arms adapted resiliently to embrace the roll between the spool heads, loops on said clamp integral with said arms and projecting outwardly in diverging directions substantially radially 30 of the roll beyond the spool heads, said loops being adapted to engage a supporting surface to prevent the roll from traveling along the surface, a resilient connection between said loops curved to conform to the curvature 35 of the roll and adapted to engage the roll with said arms, whereby the members may be urged together to separate said arms and release the roll, and the clamp being releasable by one hand of the operator engaging 40 said projecting loops, the other hand being thereby left free to hold the roll, and a non-metallic covering on said members and said curved connection to prevent marring of a supporting surface and turning of the 45 roll in said clamp.

5. A resilient clamp for the purpose specified comprising a pair of arcuate clamping arms adapted resiliently to embrace a music roll between the heads of the spool upon

which it is wound, said arms having substantially juxtaposed free ends and terminating at their other ends in outwardly projecting loops adapted to extend substantially radially of a music roll and the spool heads, the said loops being adapted to prevent the roll from traveling along a supporting surface, a resilient curved connecting strip between said loops whereby the loops may be engaged by one hand of the operator and urged together to separate the 55 clamping arms, and thereby to release the roll, the other hand of the operator being left free to hold the roll.

6. A resilient clamp for the purpose specified comprising a pair of arcuate clamping arms adapted resiliently to embrace a music roll between the heads of the spool upon which it is wound, said arms having substantially juxtaposed free ends and terminating at their other ends in outwardly 65 projecting loops adapted to extend substantially radially of a music roll and the spool heads, the said loops being adapted to prevent the roll from traveling along a supporting surface, a resilient curved connecting strip between said loops whereby the loops may be engaged by one hand of the operator and urged together to separate the 70 clamping arms, and thereby to release the roll, the other hand of the operator being 75 left free to hold the roll, said resilient connection being left free to hold the roll, said resilient connection between the loops being curved to conform with the curvature of a roll and being adapted to engage the periphery of a roll when the clamp is placed thereon, and a non-metallic covering upon 80 said loops and said resilient connection adapted to prevent marring of a supporting 85 surface and frictionally to engage said surface and the roll to prevent turning of the roll in said clamp.

In testimony whereof I affix my signature in the presence of two witnesses.
